UNITED STATES PATENT OFFICE.

TAYLOR E. DANIELS, OF CHICAGO, ILLINOIS, ASSIGNOR TO WARD S. DANIELS, OF SAME PLACE.

ROLLER-SKATE.

SPECIFICATION forming part of Letters Patent No. 616,773, dated December 27, 1898.

Application filed November 26, 1897. Serial No. 650,808. (No model.)

To all whom it may concern:

Be it known that I, TAYLOR E. DANIELS, a citizen of the United States, residing at Chicago, in the county of Cook and State of Illinois, have invented a new and useful Improvement in Roller-Skates, of which the following is a specification.

The object of my invention is to provide a generally improved but simple construction of roller-skate or "foot-cycle" whereby it shall be rendered peculiarly light, strong, easy-running, and speedy and readily interchangeable from two front wheels to one front wheel, and vice versa, whereby the spring action for controlling the steering by turning the front roller or rollers shall be adaptable to the requirements of users of different weights and whereby the wheel, with its structure reduced to the fewest possible number of parts consistent with its roller-bearing character and its purpose, shall be rendered peculiarly durable and noiseless.

Referring to the accompanying drawings, Figure 1 shows my improved roller-skate by a view in side elevation. Fig. 2 is a top plan view of the same with the rollers omitted; Fig. 3, a section taken at the line 3 on Fig. 2, viewed in the direction of the arrow and enlarged; Fig. 4, a section taken at the line 4 on Fig. 3 and viewed in the direction of the arrow; Fig. 5, a section taken at the line 5 on Fig. 3 and viewed in the direction of the arrow; Fig. 6, a section taken at the line 6 on Fig. 3 and viewed in the direction of the arrow; Fig. 7, a perspective view of a combined sleeve and washer detail; Fig. 8, a section taken at the line 8 on Fig. 2 and viewed in the direction of the arrow; Fig. 9, a view in elevation of the spring; Fig. 10, a view in side elevation of the single front wheel and its means of connection with the skate, and Fig. 11 a section taken at the line 11 on Fig. 10 and viewed in the direction of the arrow.

A is the toe portion, formed as light as possible, being preferably cast of steel, in the shape illustrated. The toe portion is equipped, in suitable position, with the adjustable sole-clamps r r' , which may be of the common variety illustrated, whereby they are adapted to slide transversely of the toe

portion, and carry on their under sides pendant bearings r' r' for the screws r^2 r^3 , engaging at their inner ends with the opposite sides of a lug r^4 . From the under side of the toe-piece A and preferably cast integral therewith there projects at a suitable inclination backward and downward (say at an inclination of about forty-five degrees) a tubular spring housing A', containing near its upper end a transverse diaphragm p , Fig. 3, having a central opening p' , affording a bearing, and containing also, in alinement with each other and projecting inward from its wall, a lug o adjacent to the diaphragm and a lug o' adjacent to an annular offset o^2 formed about the inner side of the housing, near its outer end.

A^2 is a rotary stem, Figs. 3 and 10, having reduced threaded ends, at one of which it passes through the opening p' in the diaphragm and is held, as by a nut p^2 , (accessible through the opening shown in Fig. 2 to be provided about the center of the toe-piece,) to extend lengthwise through the center of the housing, and the stem carries near its outer end a disk-shaped head n , adapted to seat against the offset o^2 and affording on its outer side a cup for the balls q of a ball-bearing device of usual or any suitable general construction, the cone n' of which is screwed upon the outer reduced end of the stem A^2 , in which position it may be locked against turning on the stem by a pin x . Inside the housing A' and abutting against the diaphragm therein is loosely confined about the stem a combined sleeve and washer device B, comprising a sleeve m , having the offset m' , and provided with an annular head or washer m^2 , containing a segmental recess m^3 in its edge and an opening m^4 opposite the recess. A device B', similar in form and construction to the device B, is loosely adjusted about the stem A^2 near its outer end, as shown in Fig. 3. The parts m of the two devices B and B' abut, while between the offsets m' of the two a rectangular recess is formed, through which there projects from the stem A^2 a lug v to engage, by turning the stem, with either edge of the aforesaid recess, for a purpose hereinafter described. The lugs o 100

and o' are embraced, respectively, by the recesses m^3 in the annular heads of the devices B and B', and in the housing about the adjacent sleeves m of these two devices is confined a coiled spring B², having its ends turned outward in alinement with each other, as shown at m^5 m^6 in Fig. 9, and respectively inserted into the openings m^4 of the washers m^3 of said two devices B and B'. In adjusting this spring to insert its ends into the openings m^4 it is set or flexed by slightly straining the coil backward at its ends in opposite directions—that is, in the direction of uncoiling it. About the head n is fastened (as by screwing with a screw v' or pin, inserted to prevent independent rotation) a ring C, having an axle-bearing C' extending from it for the front axle C². This bearing may be in the form of that represented most clearly in Figs. 4 and 6 for use with the skate when two front wheels D are employed, one on each end of the axle, with the bearing between them, or it may be in the yoke form most clearly represented in Fig. 11 for use where a single front wheel D is employed, in which latter form it supports the axle at each end and embraces the wheel.

The construction renders exchanging single and double front wheels one for the other a matter of ease, since to effect the change it is only necessary on unscrewing the nut p^2 to withdraw from the skate the stem A² and parts it carries, as shown by Fig. 10, and substitute therefor the stem of the other wheeled device desired, meantime readjusting the spring B² and devices B and B'.

From the foregoing description of the spring B² and its coöperating parts it will be seen that its normal tension may be regulated to any requirement by tightening or loosening it by the desired number of turns in the proper direction of the lower device B and that in steering by turning the front wheel or wheels on the axis afforded by the stem A², whereby through the medium of the lug v , engaging the devices B B', an abnormal tension is exerted in contrary directions against the opposite ends of the spring, the latter will, when relieved of the strain of turning, by its recoil readjust the front wheel or wheels into normal alinement with the foot portion of the skate.

E is the heel portion of the skate, preferably of cast-steel, like the toe portion, and of the light frame shape illustrated, being equipped with bearings l for the axle C³ of the rear wheel D' and with heel-clamps r' , which may be and are shown to be the same as to their form and the mechanism for supporting and adjusting them as the clamping device for the toe portion of the skate, already described.

The diameter of the rear wheel D' is by preference materially greater than that of the front wheel or wheels, thereby to increase the speed of the skate accordingly.

Each of the wheels may involve the same construction, which is preferably the follow-

ing and of the ball-bearing variety: If is a sleeve having internal annular offsets t and t' (see Fig. 11) formed at opposite sides of its circumferential center about its interior and affording abutments for the cups k k' of the ball-bearing devices, the balls k' of which are confined in place in a usual or any suitable manner, as by the cones k^2 . About the sleeve is provided the tire seat or rim, shown as formed of an internally-shouldered flange i , extending about the sleeve at one side of its circumferential center and integral therewith, and an annular flange i' , of similar form, removably secured, as by screwing, upon the sleeve to extend short of its circumferential center at the opposite side thereof. Thus a space is left between the neck portions of the two flanges, which I fill with an annular spacing-disk h , formed, preferably, of wood. In the rim is seated the tire G, thus against the shoulders of the flanges i i' and the filler h , whereby a solid bearing is afforded to it, the tire being formed as to its body portion of hard material, preferably very hard rubber. To protect the material forming the body of the tire against fracture and at the same time to render the wheel noiseless, or comparatively so, an annular recess g , Fig. 4, is formed about the tread portion, and in this recess I wind and thus fill it to form the tread any suitable thread-like material G', preferably stout linen braid or twine preparatorily soaked in rubber solution and dried.

H is a reach for separably connecting the wheel portion E with the toe portion A. It comprises a tongue, best formed of sheet metal, connected at one end to the heel portion E and containing a longitudinal slot s toward its forward end, where it is confined to be longitudinally adjustable in a groove d formed in the base of the toe portion A to extend lengthwise thereof, the reach being firmly held in any position to which it is adjusted by a clamp-bolt s' . On loosening the bolt s' the reach may be extended or contracted to adjust the length of the skate according to requirement, and on withdrawing the bolt the reach may be pulled away entirely to separate the heel portion of the skate from the toe portion, and thus permit the latter to be used alone, as for fancy skating.

What I claim as new, and desire to secure by Letters Patent, is—

1. In a roller-skate, the combination with the toe portion of a stem carrying the front-axle bearing and supported to rotate on its axis by turning the front wheel or wheels, a spring controlling the rotation of said stem, and means for confining said spring and for adjusting the tension thereof, substantially as described.

2. In a roller-skate, the combination with the toe portion of a housing projecting from the base thereof, a stem carrying the front-axle bearing and confined in said housing to rotate on its axis by turning the front wheel or wheels, a spring in the housing controlling

the rotation of said stem, and means for confining said spring in place and for adjusting the tension thereof, substantially as described.

3. In a roller-skate, the combination with 5 the toe portion of a housing projecting from the base thereof, a stem rotatably confined in said housing and carrying the front-axle bearing, a coiled spring B² surrounding said stem in the housing and having the outward-turned 10 ends at which it is confined to be tensioned in contrary directions toward its opposite ends by turning said stem, substantially as described.

4. In a roller-skate, the combination with 15 the toe portion of a housing projecting from the base thereof, a stem confined in said housing, a front-axle bearing having a roller-bearing connection with said stem, said stem being supported to rotate on its axis by turning 20 the front wheel or wheels and a spring confined in said housing to control the rotation of said stem, substantially as described.

5. In a roller-skate, the combination with 25 the toe portion of a housing projecting from the base thereof, a stem rotatably and removably confined in said housing, a front-axle bearing having a ring at which it is connected with said stem through the medium of a roller-bearing thereon, and a spring confined in 30 said housing to control the rotation of said stem, substantially as described.

6. In a roller-skate, the combination with the toe portion of a housing A' projecting from the base thereof, and containing the

lugs o, o', a stem A² rotatably supported at 35 one end in said housing and carrying at its opposite end a roller-bearing device, a spring B² around said stem, the combined sleeve and washer devices B and B' in the housing about the stem, engaging with said lugs and engaged 40 by the ends of the spring, and a front-axle bearing extending from said roller-bearing, substantially as described.

7. In a skate-roller, the tire formed of hard material, such as hard rubber, and provided 45 with a circumferential recess in its tread portion, and a filling in said recess comprising a suitable thread-like material forming the tire-tread, substantially as described.

8. In a skate-roller, the tire formed of hard 50 rubber, or the like, and provided with a circumferential recess in its tread portion, and a filling in said recess comprising rubber-so- lutioned thread-like material, wound into the recess and forming the tire-tread, substan- 55 tially as described.

9. A skate-roller comprising, in combination with a shaft and roller-bearings thereon, a sleeve F surrounding said shaft and bearings and carrying the rim, a filling h between 60 the rim-sections, and a tire of hard rubber, or the like, confined in said rim, substantially as described.
